UNITED STATES PATENT OFFICE.

VICTOR S. PEARLMAN, OF CHICAGO, ILLINOIS.

TABLE LAMP.

Application filed November 21, 1927. Serial No. 234,589.

This invention relates to improvements in table lamps of the disappearing type and has for its principal object to provide a new and improved construction whereby the lamp 5 may be automatically lighted when it is in raised position and extinguished when lowered.

A further object is to provide an improved construction of extensible lamp shield which 10 is automatically closed when the lamp is lowered. A further object is to provide an improved form of marginal frame especially adapted for use with glass table tops whereby 15 said tops will be protected from injury or breakage due to operation of the lamp.

Other objects of the invention will appear from time to time as the description proceeds.

The invention may best be understood by reference to the accompanying drawings in 20 which Figure 1 is a longitudinal section of the device constructed in accordance with my invention and showing the lamp body in fully raised position.

Figure 2 is a transverse section of the device but with the lamp body shown in its lowered position and with the outside casing omitted.

Figure 3 is a detailed sectional view showing one end of the lamp casing, with the lamp 30 body in partially raised position to show the arrangement of the light switch and its contacts.

Figure 4 is a detailed sectional view showing the lamp shade in extended position but 35 in coacting relationship with the marginal frame so as to automatically close said lamp shade when the lamp body is lowered.

Referring now to details shown in the drawings, the invention is shown as applied 40 to a desk lamp consisting of a lamp body 11 having a shade 12, preferably rectangular in form and open at the bottom so as to shed rays from the lamp 14 therein in a downwardly direction. The shade 12 is supported by two 45 uprights 16, 16, on the horizontally disposed base plate 17. The lamp body 11 including the shade 12, base plate 17 and supports 16, 16, constitutes a unitary structure arranged to be moved vertically with respect to the top 50 of the table or desk 10.

Any suitable means may be utilized for elevating the lamp body, in the form herein shown, the elevating means being of the spring motor type broadly disclosed in co-pending application of William Podrouzek,

filed November 9, 1927, and bearing Serial No. 232,026. Details of this elevating mechanism need not be described herein as it forms no part of the present invention excepting to point out that the spring motor 40 drives 60 shaft 41 having beveled gears 46 thereon which engage beveled gears 47 on a pair of longitudinally disposed shafts 48. Pinions 31, 31, are disposed at opposite ends of shafts 48, 48, and engage vertically disposed racks 65 32, 32, on upright corner frame members 55, 55.

Referring more particularly to the features of the present invention I provide an improved automatic switch device whereby the 70 lamp 14 is automatically lighted when the lamp body is in its fully raised position. As will be seen in Figures 1 and 3 a pair of conductors 50 and 51 lead from the lamp base 14 down the adjacent support 16 and from 75 thence to a pair of terminals 52 and 53 respectively, mounted on a cross brace 54, preferably of insulating material, carried on downwardly extending guide members 49, 49, at one end of the base plate 17. A pair of 80 spring contacts 58, 59, are connected to the terminals 52 and 53 respectively, and are bent downwardly in position to engage relatively fixed contacts 58^a and 59^a supported on an insulating piece 54^a adjacent the upper 85 ends of the upright frame members 55, 55. These fixed contacts 58^a and 59^a are provided with suitable terminals 58^b and 59^b projecting outwardly from the insulating piece 54^a in position to be engaged by a detachable 90 circuit plug of any suitable construction. The arrangement is such that spring contacts 58 and 59 engage their respective fixed contacts 58^a and 59^a only when the lamp body is in fully raised position, and are disengaged 95 therefrom as soon as the lamp body is lowered, thereby automatically cutting off the source of current supply when the lamp is lowered and not in use.

In connection with the lamp shade 12, I 100 provide a shade portion 72 pivoted near its upper margin on hinge 73 so that said shade portion may be pulled outwardly to afford an increased spread of light when the lamp is in use, as shown in Figure 4. In order to 105 insure the proper closing of this shade portion 72 when the lamp body is lowered, I provide a depending cam arm 74 attached to the lower margin of shade portion 72 and extending inwardly therefrom in a position to en- 110

gage the marginal frame 21 when the lamp shade is lowered, thereby causing the shade portion 72 to be automatically closed, as indicated in Figure 4.

5 I find further that in applying a lamp or similar disappearing stand to tables having glass tops it is desirable to secure the marginal frame member 21 to the wooden portion of the table but to raise the upper surface of
10 the marginal frame 21 to the same level as the upper surface of the glass top. Accordingly, as shown in the drawings, I provide a marginal frame with an outwardly flanged portion 21^a and a downwardly extending
15 marginal flange 21^b of the same height as the thickness of the glass top to be used therewith. With this construction, the frame may be readily set in place and secured to the wooden base of the table top. The glass top
20 may then be applied in a position which will be found to be flush with the top of the marginal frame 21. Furthermore, the glass top is cut so as to fit snugly around the frame 21 and will be protected by the latter from accident
25 dental breakage or injury incident to the raising and lowering of the lamp body.

Although I have shown and described the particular embodiment of my invention, it will be understood that I do not wish to be limited to the construction shown and described, but that various changes and modi-

fications may be made without departing from the spirit and scope of my invention.

I claim:

1. In combination with a table top having an aperture, a disappearing lamp body movable vertically in said aperture and including a shade and support therefor, said shade having a movable portion extensible laterally beyond the margin of said aperture when said shade is in raised position, and means carried by said extensible shade portion coacting with the table top for automatically returning said shade portion to closed position when said shade is lowered into said aperture. 35

2. In combination with a table top having an aperture, a disappearing lamp body movable vertically in said aperture and including a shade and support therefor, said shade having a movable portion extensible laterally beyond the margin of said aperture when said shade is in raised position, and cam means extending downwardly from said extensible shade portion coacting with the table top for automatically returning said shade portion to closed position when said shade is lowered into said aperture. 40 45 50 55

Signed at Chicago, Ill., this 17th day of November, 1927.

VICTOR S. PEARLMAN.
